RAILWAY SIGNALING APPARATUS

Charles W. Failor, Forest Hills, Pa., assignor to
The Union Switch & Signal Company, Swiss-
vale, Pa., a corporation of Pennsylvania

Application August 16, 1940, Serial No. 352,936

9 Claims. (Cl. 246—33)

My invention relates to railway signaling apparatus and more particularly to apparatus of this character in which provision is made for traffic movements in either direction over the same stretch of track.

My invention is particularly well adapted for, though in no manner limited to, coded train control in reverse-running territory, either with or without wayside signals, of the type in which the train control code is approach controlled. That is to say, the track circuits when unoccupied are normally energized with the usual coded track circuit current but become automatically energized with train control code upon the approach of a train.

One object of my invention is to enable the same coded track circuit control equipment to be used for traffic moving in either direction. Another object of my invention is to use standard apparatus such as is used in single-direction running track circuits, for performing a dual function depending on traffic direction. A further object of my invention is to provide a simple, effective, and safe arrangement of apparatus and circuits for controlling the movement of traffic in either direction through the section. Other objects, purposes and features of my invention will be apparent from the description which follows.

I accomplish the foregoing objects by making one relay perform the function of a track relay for one direction of traffic and causing the same relay to function as an impulse receiving relay for approach control purposes when the traffic is in the other direction. Likewise, that relay which performs the function of a code repeater for one direction of traffic automatically becomes an impulse transmitting relay for approach control when traffic is set up in the opposite direction.

I shall describe one form of apparatus embodying my invention and shall then point out the novel features thereof in claims.

In the accompanying drawings, Figs. 1a and 1b when placed end to end with Fig. 1a at the left, show a stretch of single track railway equipped with apparatus embodying my invention. The apparatus of Fig. 1b is essentially a duplicate of the apparatus of Fig. 1a and is shown in order to make more clear the operations involved in the passage of a train through the section.

Similar reference characters refer to similar parts in each of the two views.

Referring to the drawings, the section D—E is equipped with similar wayside apparatus at each end of the section for the purpose of controlling traffic passing in either direction through the section. Phantom wayside signals for each direction are shown in dotted lines at the loca-

tions D and E as a means of indicating that it is at these locations that a change may occur in the train controlling current for an approaching train and that wayside signals, if used, would normally be placed at these locations. I shall first describe the individual apparatus at location D and shall then point out how this apparatus cooperates with the apparatus at the other end of the section during the passage of a train.

Looking at location D, the relay DS is the direction selecting relay which functions to establish the direction of traffic through the section in accordance with the position occupied by its polar contacts. The polar contact 1 occupies the normal or left-hand position, as shown, for eastbound train movements and the reverse or right-hand position for westbound train movements. The specific manner in which relay DS is controlled forms no part of my invention and is not shown, for simplicity. This directional control can be exercised by any suitable and well-known traffic reversal circuit. Relays DSEM and DSWM are repeater relays which repeat the normal and reverse position, respectively, of the direction selector relay DS. The energizing circuit for relay DSEM includes front contact 2 of relay DS, polar contact 1 in the normal position, and back contact 3 of relay DSWM. Similarly, the energizing circuit for relay DSWM includes front contact 2 of relay DS, polar contact 1 in the reverse position, and back contact 4 of relay DSEM.

The track connected relay at location D is designated by the reference character TR with a suffix corresponding to the location, this same suffix being used in conjunction with most of the apparatus at location D. The suffix E designates, for the most part, the apparatus at location E. With relay DS in the normal or eastbound position as shown, relay TRD performs the functions of the usual code following track relay as will be explained hereinafter, and relay CRD is then an approach impulse transmitting relay. Relay 2TR under that condition functions as an approach impulse receiving relay and relay 2CR functions as a code repeating relay which repeats the operation of coder CT180 or CT75 (depending on traffic conditions) and supplies the track circuit code which operates track relay TRD.

The track circuit code impulses for eastbound traffic are supplied from a suitable track battery TB over an adjustable current limiting resistor R, the secondary winding of the track transformer 2TT, and front contact 5 of the code repeating relay 2CR. Under proper conditions, the track transformer secondary will be supplying alternating current which will be coded over contact 5 of relay 2CR and supplied to the track as train control code for the eastbound train.

Relay TRD in following the track circuit code, periodically reverses the flow of current in the input winding 6 of the decoding transformer DTD, over its reversing contact 7, thereby inducing current impulses of corresponding code in the two output windings 8 and 9. The circuit for energizing the input winding 6 may be traced from one terminal B of a suitable source of unidirectional current, neutral contact 10 of relay DS, polar contact 11 in its normal position, wire 12, contact 7 of relay TRD in either its up or down position, and winding 6, to the other terminal C of the source. The output from winding 9 is rectified over a second contact 13 of relay TRD and is used for energizing the decoding relay HD over the polar contact 14 of relays DS as long as one of the relays TRD or 1TR is following code. The latter relay will be effective as a track relay for westbound traffic and will perform the corresponding pole changing and rectifying functions over its contacts 15 and 16, respectively, as will become clear hereinafter. The decoding transformer DTD has its input pole changed over contact 7 of relay TRD for eastbound moves and over contact 15 of relay 1TR for westbound moves.

The relay CRD, as pointed out before, functions either as an approach impulse transmitting relay or as a code repeater depending upon whether the traffic is eastbound or westbound, respectively. When conditions are established for eastbound traffic, as shown in the drawings, relay CRD performs its impulse transmitting function by virtue of energy impulses which it receives from the upper secondary winding 8 of the decoding transformer DTD. The energizing circuit for relay CRD may be traced from the upper terminal of winding 8, wire 17, front contact 18 of relay DSEM, wire 19, and winding of relay CRD, to the lower terminal F of winding 8. Relay CRD is of the polarized direct current type, closing its front contact 20-a when current of normal polarity is applied thereto and closing its back contact 20-b when current of reverse relative polarity is effective.

The impulse delivered from winding 8 when contact 7 is closed in its up position is of reverse polarity so that at such time the relay CRD is caused to keep its back contact 20-b closed. When contact 7 closes in its down position, an impulse of normal polarity is delivered to relay CRD so that contact 20-a will close. Accordingly, it will be apparent that for eastbound traffic, each time that relay TRD is de-energized, relay CRD will transmit an approach impulse of current from battery TB over its front contact 20-a to the impulse receiving relay 2TR at location E. The primary winding of transformer TTD is maintained short-circuited at such time over back contact 21 of relay DSWM to reduce arcing at the contacts of relay CRD.

Relay 2TP at location E is a slow release repeater of front contact 22 of relay 2TR or of front contact 23 of relay TRE depending upon the traffic direction. For eastbound traffic, relay 2TP is energized over a circuit which includes front contact 22, wire 24, normal contact 25-a of relay 2DS, front contact 26, and wire 27, to relay 2TP. For westbound traffic, the energizing circuit is the same except that it includes front contact 23 of relay TRE, wire 28, and reverse contact 25-b of relay 2DS. Relay 2TP is normally energized but becomes de-energized when an eastbound train enters the sec-

tion, and supplies cab signal energy to the primary winding of track transformer 2TT over a circuit which may be traced from one terminal BX of a source of alternating current, back contact 29 of relay 2TP, wire 30, front contact 31 of relay 2DSEM, wire 32, winding of transformer 2TT, and wires 33 and 34, to the other terminal CX of the source. This energy is coded in the track by virtue of the operation of contact 5 of code repeating relay 2CR.

For the other traffic direction, relay 1TP at location D becomes deenergized when a westbound train enters the section, and supplies cab signal energy to the primary winding of track transformer TTD over a circuit which may be traced from one terminal BX of a source of alternating current, back contact 35 of relay 1TP, wire 36, front contact 21 of relay DSWM, wire 37, winding of transformer TTD, and wire 38, to the other terminal CX of the source. As in the case of eastbound traffic, this cab signal energy is coded in the output circuit of the track transformer by means of the operation of contact 20-a of the code repeating relay CRD.

Having described the individual apparatus, I shall now describe the manner in which the apparatus functions when a train passes through the section.

Normally, when the section D-E is unoccupied as shown in the drawings and the relays DS and 2DS are set up for an eastbound traffic move, with the section next in advance of D-E also unoccupied, the relay TRE will be following code and will thereby maintain decoding relay HE energized so that 180 code will be furnished to code repeating relay 2CR over the following circuit: contact 39 of code transmitter CT199, wire 40, front contact 41 of relay HE, wires 42 and 43, front contact 44 of relay 2DSEM, and wire 45, to relay 2CR. Relay 2CR will follow 180 code and in so doing will repeat this code into the track section D-E by virtue of the periodic closing of its front contact 5 which causes impulses of current from battery TB to be supplied to the rails. The primary winding of transformer 2TT will be short-circuited at this time over front contact 29 of relay 2TP and front contact 31 of relay 2DSEM.

Relay TRD will follow the code transmitted by relay 2CR and will cause impulses of the proper polarity to be induced in winding 8 of the decoding transformer DTD to thereby operate polarized relay CRD in such a manner that back contact 20-b will be closed when relay TRD is up and front contact 20-a will be closed when relay TRD is down, as explained hereinbefore.

Relay HD will be up as a result of the code following action of relay TRD, so that 180 code will be supplied to relay 1CR over a circuit identical with that traced for relay 2CR, as described above. Accordingly, 180 code will be supplied to the section to the left of location D.

Each time that relay CRD closes its front contact 20-a, an approach code impulse is transmitted from battery TB over the rails to relay 2TR which is the approach impulse receiving relay under the eastbound traffic condition which has been assumed. It will be noted that when relay CRD is up, relay 2CR will be down, so that relay 2TR will receive the approach impulse transmitted by relay CRD over back contact 5 of relay 2CR. Also, when relay 2CR is up, relay CRD will be down, so that relay TRD will receive the track circuit code impulse trans-

mitted by relay 2CR over back contact 20-b of relay CRD.

Relay 2TR in following the approach code will maintain relay 2TP picked up because of the periodic closing of front contact 22 of relay 2TR. Accordingly, no train control code will be supplied to the rails of section D-E under the assumed condition of unoccupancy.

When an eastbound train enters the section to the left of section D-E, relay 1TR will become deenergized so that relay 1TP will release and in so doing will cause alternating current to be supplied to the primary winding of transformer 1TT. This alternating current will be transformed into 180 train control code by virtue of the 180 code operation of relay 1CR whereby the train carried receiving apparatus will provide a suitable cab signal indication showing that the advance section D-E is unoccupied.

When the train enters section D-E, relay TRD will become deenergized, causing relay CRD to become deenergized also, whereupon relay 2TR will cease its code following action and will also remain deenergized. Relay 2TP will release and will cause the application of 180 train control code at the exit end of section D-E, as previously explained for the approach section. If the section immediately in advance of location E is occupied at the time the train enters section D-E, relay HE will be released so that 75 code will be supplied to the train because relay 2CR will be responding to 75 code supplied over contact 46 of code transmitter CT75. Thus, the cab signal will indicate caution until such time as the advance section becomes unoccupied.

When the train fully clears section D-E, all of the apparatus of this section will be restored to the normal condition in which it is shown except that the deenergization of relay HE due to the release of relay TRE will cause 75 code to be effective in the section so that relays TRD, CRD, 2TR, and 2CR will all be following 75 code instead of 180.

When the train vacates the section immediately in advance of location E, relay TRE will begin to follow code so that relay HE will pick up and will thereby restore 180 code to section D-E. Under this condition, all of the apparatus will be restored to the condition in which it is illustrated in the drawings.

If it is desired to permit a westbound train to pass through the section, direction selecting relays DS and 2DS will be operated so that polar contact 1 occupies the right-hand or reverse position which will cause relays DSWM and 2DSWM to pick up and relays DSEM and 2DSEM to release. Relay CRD will now become a code repeating relay which will repeat the operation of code transmitter CT180 at location D by virtue of its energizing circuit which includes: contact 39, wire 49, front contact 41 of relay HD, wires 42 and 47, front contact 48 of relay DSWM, and wire 19, to relay CRD. Relay CRD will transmit an impulse from battery TB each time that its front contact 20-a is closed, for operating relay 2TR which now becomes a track relay for westbound traffic. The primary winding of transformer TTD is maintained short-circuited over front contacts 21 and 35 of relays DSWM and 1TP, respectively.

Relay 2TR, in operating, will cause impulses to be induced in winding 8 of decoding transformer DTE which will in turn cause code operation of relay 2CR as previously explained. This relay now becomes the approach code transmit-

ting relay for westbound traffic. The operation, as explained hereinbefore, is such that when relay 2CR is up to transmit a code impulse, relay CRD is down so that relay TRD is connected with the rails for receiving the impulse. Also when relay CRD is up for transmitting its respective impulse, relay 2CR is down so that relay 2TR may respond. Relay TRD becomes the approach code receiving relay for westbound traffic.

When a westbound train enters section D-E, relay 2TR will cease to follow code so that relay 2CR will become deenergized. Relay TRD will accordingly cease to follow code so that relay 1TP will release due to the opening of the energizing circuit for this relay at front contact 23 of relay TRD. Relays HD and CRD will not, however, become deenergized because of the continued operation of relay 1TR which energizes the decoding transformer DTD over its contact 15. The primary winding of transformer TTD will be energized with alternating current over the front contact 21 of relay DSWM and back contact 35 of relay 1TP, and the cab signal code transmitted by relay CRD will be 180 since relay HD is energized. A proceed signal will therefore be displayed on the train. If the section to the left of location D happens to be occupied at the time, relay HD will be released so that 75 code will be effective in the rails of section D-E to cause a caution cab signal indication to be effective in this section.

When the westbound train vacates section D-E but still occupies the section to the left of location D, relay CRD will be repeating 75 code and relays TRD, 2TR, and 2CR will all be operating at 75 code. Then, when the section to the left of location D is cleared, pick-up of relay HD will cause relay CRD to repeat 180 code whereupon relays TRD, 2TR, and 2CR will operate at 180 code so that all of the apparatus will be restored to the condition in which it is shown except for the direction selecting relays DS, DSEM, and DSWM which have been assumed set up for westbound traffic.

The circuits as shown are for two-block signaling but it is obvious that these could readily be expanded into three-block signaling, if desired, without altering the novel features of the apparatus. Also, if wayside signals are used, these can be approach lighted over a back contact of relay 1TP or 2TP so that the approach feature may be applied either to cab signals or wayside signals, or to both.

It will be obvious from the foregoing that I have provided a single track system over which traffic may move in either direction, in which approach control is effective and in which a minimum number of code following relays are employed, the functions of certain of these relays being interchanged depending on traffic direction. I have further provided a system of the above character in which the operations are performed in a simple, safe, and reliable manner.

Although I have herein shown and described only one form of railway signaling apparatus embodying my invention, it is understood that various changes and modifications may be made therein within the scope of the appended claims without departing from the spirit and scope of my invention.

Having thus described my invention, what I claim is:

1. In combination with a section of railway track over which traffic may move in either direction, traffic direction selecting means having

a normal and a reverse position for establishing eastbound and westbound traffic conditions respectively in said section, an eastbound code repeating relay adjacent the eastbound exit end of said section effective when said selecting means occupies its normal position for supplying current impulses of an eastbound track circuit code to the rails of said section, an eastbound code following track relay adjacent the eastbound entrance end of said section responsive to impulses of said track circuit code which it receives from said section, an eastbound approach impulse transmitting relay adjacent said eastbound entrance end effective during off intervals between impulses of said track circuit code for supplying current impulses of an eastbound approach code to the rails of said section, an eastbound approach impulse receiving relay at said eastbound exit end responsive to the impulses of said approach code which it receives from said section, and circuit means effective when said direction selecting means is reversed to establish westbound traffic conditions in said section for causing said eastbound impulse transmitting relay to function as the westbound code repeating relay by supplying current impulses of a westbound track circuit code at the westbound exit end of said section to thereby cause said eastbound impulse receiving relay to function as the westbound track relay by responding to impulses of said westbound track circuit code, said circuit means being also effective under said westbound traffic conditions for causing said eastbound code repeating relay to function as the westbound approach code transmitting relay by supplying current impulses of a westbound approach code to the rails of said section to thereby cause operation of said eastbound track relay as a westbound approach code receiving relay.

2. In combination with a section of railway track, a code repeating relay and an approach impulse receiving relay both adjacent one end of said section, means including a front contact of said code repeating relay for supplying current impulses of a track circuit code to the rails of said section, a track relay and an approach impulse transmitting relay both adjacent the other end of said section, means including a back contact of said code repeating relay for periodically connecting said approach impulse receiving relay in energy receiving relation with the rails of said section, means including a front contact of said approach impulse transmitting relay for supplying current impulses of an approach code to the rails of said section to operate said approach impulse receiving relay, means including a back contact of said approach impulse transmitting relay for periodically connecting said track relay with said rails to receive current impulses of said track circuit code, and means effective each time said track relay is released for supplying an impulse of current to said approach impulse transmitting relay to cause code operation thereof.

3. In combination with a section of railway track; a code repeating relay, an approach impulse receiving relay, a slow acting repeater of said approach impulse receiving relay, and a normally deenergized track transformer all adjacent one end of said section; a track relay and an approach impulse transmitting relay both adjacent the other end of said section, means including a front contact of said approach im-

pulse receiving relay for energizing said slow acting repeater, means including a back contact of said slow acting repeater effective when a train enters said other end of the section for energizing the input winding of said transformer with alternating current, means for operating said code repeating relay at code intervals, means including a front contact of said code repeating relay effective when said input winding is energized for transmitting coded alternating current cab signal impulses to the train over said section from the output winding of said transformer, said code repeating relay also supplying current impulses of a track circuit code over a front contact thereof to said section, means including a back contact of said approach impulse transmitting relay for periodically connecting said track relay across the rails of said section to cause operation thereof on said track circuit code when the section is unoccupied, means including a front contact of said slow acting repeater for normally short-circuiting said transformer input winding to thereby decrease the effective impedance of said output winding and aid the supply of track circuit code by said code repeating relay, means governed by said track relay when operating on said track circuit code for causing code operation of said approach impulse transmitting relay alternately with its own code operation, means including a front contact of said approach impulse transmitting relay for supplying current impulses of an approach code to said section, and means including a back contact of said code repeating relay for periodically connecting said approach impulse receiving relay with the rails of said section for operation by said approach code.

4. In combination with two adjoining sections of railway track, a track relay and an approach impulse transmitting relay for the forward section, an approach impulse receiving relay for the rear section, means including a back contact of said impulse transmitting relay for connecting said track relay with the rails of said forward section, means for supplying current impulses of a track circuit code to said forward section to thereby cause code operation of said track relay, a decoding transformer for said forward section, means effective when said track relay is operating on said track circuit code and traffic conditions are eastbound in said two sections for supplying impulses of current to said decoding transformer to thereby cause an impulse output to be delivered therefrom, means effective under said eastbound traffic conditions for applying said impulse output to said impulse transmitting relay to cause operation thereof, means for supplying impulses of current to the rails of said rear section to thereby cause code operation of said impulse receiving relay, means governed by said impulse receiving relay when responding to code and effective under westbound traffic conditions for supplying impulses of current to said decoding transformer, and means controlled by the impulse output from said decoding transformer effective under said westbound traffic conditions for causing code operation of said impulse transmitting relay.

5. In combination with two adjoining sections of railway track, a track relay and an approach impulse transmitting relay for the forward section, an approach impulse receiving relay for the rear section, means including a back contact of said impulse transmitting relay for connecting said track relay with the rails of said forward

section, means for supplying current impulses of a track circuit code to said forward section to thereby cause code operation of said track relay, a decoding transformer for said forward section, a traffic direction selector for said two sections, means effective when said track relay is operating on said track circuit code and said selector occupies its eastbound position for supplying impulses of current to said decoding transformer to cause an impulse output to be delivered therefrom, means effective when said selector occupies its eastbound position for applying said impulse output to said impulse transmitting relay to cause code operation thereof whereby an approach code is transmitted to said forward section, means for supplying impulses of current to the rails of said rear section to thereby cause code operation of said impulse receiving relay, means governed by said impulse receiving relay when responding to code and effective when said selector occupies its westbound position for supplying impulses of current to said decoding transformer, and means controlled by the impulse output from said decoding transformer effective when said selector occupies its westbound position for causing code operation of said impulse transmitting relay.

6. In combination with a section of railway track, a code repeating relay and an approach impulse receiving relay adjacent one end of said section, a track relay and an approach impulse transmitting relay adjacent the other end of said section, traffic direction selecting means, means controlled by said direction selecting means for operating said code repeating relay on code, means including a front contact of said code repeating relay for supplying current impulses of a track circuit code to the rails of said section, means including a back contact of said code repeating relay for periodically connecting said approach impulse receiving relay to receive energy from the rails of said section, means including a back contact of said approach impulse transmitting relay for periodically connecting said track relay with the rails for response to said track circuit code, a normally deenergized decoding relay responsive to code operation of said track relay, means controlled by said decoding relay for selecting the code effective in the section to the rear of said section, means responsive to code operation of said track relay for causing code operation of said approach impulse transmitting relay, and means including a front contact of said last-named relay for supplying current impulses of an approach code to the rails of said section to thereby operate said approach impulse receiving relay.

7. In combination with a section of railway track over which traffic may move in either direction, a first code transmitting relay and a first code receiving relay adjacent one end of said section, a second code transmitting relay and a second code receiving relay adjacent the other end of said section, traffic direction selecting means having a normal position for eastbound traffic and a reverse position for westbound traffic through said section, means effective when said selecting means is in its normal position for causing said first transmitting relay to supply current impulses of a track circuit code to said section in accordance with traffic conditions in advance thereof to cause code operation of said second receiving relay, means controlled by said second receiving relay effec-

tive when said selecting means is in its normal position for causing said second transmitting relay to supply current impulses of an approach code to said section to cause code operation of said first receiving relay, and means effective when said selecting means is in its reverse position for interchanging the code transmitting function of said first transmitting relay with the code transmitting function of said second transmitting relay and for interchanging the code receiving function of said first receiving relay with the code receiving function of said second receiving relay.

8. In combination with a section of railway track over which traffic may move in either direction, a first code transmitting relay and a first code receiving relay adjacent one end of said section, a second code transmitting relay and a second code receiving relay adjacent the other end of said section, two traffic direction selectors, means effective when the first selector occupies its eastbound position for causing the first transmitting relay to supply current impulses of a track circuit code to said section in accordance with traffic conditions in advance thereof to cause code operation of said second receiving relay, means controlled by said second receiving relay effective when the second selector occupies its eastbound position for causing said second transmitting relay to supply current impulses of an approach code to said section to cause code operation of said first receiving relay, and means effective when both said selectors occupy their westbound position for interchanging the code transmitting function of said first transmitting relay with the code transmitting function of said second transmitting relay and for interchanging the code receiving function of said first receiving relay with the code receiving function of said second receiving relay.

9. In combination with a section of railway track over which traffic may move in either direction, a first code transmitting relay and a first code receiving relay adjacent one end of said section, a second code transmitting and a second code receiving relay adjacent the other end of said section, traffic direction selecting means having a normal position for eastbound traffic and a reverse position for westbound traffic through said section, means effective when said selecting means is in its normal position for causing said first transmitting relay to supply current impulses of a track circuit code to said section to cause code operation of said second receiving relay, means controlled by said second receiving relay effective when said selecting means is in its normal position for causing code operation of said second transmitting relay alternately with its own code operation to thereby cause said second transmitting relay to supply current impulses of an approach code to said section, means controlled by said first transmitting relay for causing code operation of said first receiving relay on said approach code, and means effective when said selecting means is in its reverse position for interchanging the code transmitting function of said first transmitting relay with the code transmitting function of said second transmitting relay and for interchanging the code receiving function of said first receiving relay with the code receiving function of said second receiving relay.
